UNITED STATES PATENT OFFICE.

GEORGE E. HOARD, OF WASHINGTON, DISTRICT OF COLUMBIA.

RESILIENT WHEEL.

1,402,069.

Specification of Letters Patent. Patented Jan. 3, 1922.

Application filed January 10, 1920. Serial No. 350,662.

To all whom it may concern:

Be it known that I, GEORGE E. HOARD, a citizen of the United States, residing at Washington, in the District of Columbia, 5 have invented certain new and useful Improvements in Resilient Wheels, of which the following is a specification.

This invention relates to improvements in resilient wheels generally and particularly 10 to what is known as cushion wheels of that type having a hub element with a free independent floating movement.

The present improvement contemplates and has for one of its objects the provision 15 of a sensitively resilient wheel wherein a pneumatic tube and relative structures commonly associated with such tubes are entirely eliminated without sacrificing the requisite and practical shock and vibration absorbing characteristics which should be resi- 20 dent in an easy riding and stress compensating durable wheel of this class.

A further object of the invention is to 25 provide a novel form of shock or vibration absorbing means strongly constructed and anti-frictionally coordinated in a particular manner to effect an equal distribution of the vehicle or weight load on all points of contact irrespective of position of the same, and 30 thereby materially reduce wear on the co-acting parts and essentially add to the practicability and efficiency of the general organization of the wheel.

A further object of the invention is to 35 generally improve cushion wheels by structurally reducing the components in number as much as possible, and producing them in such similar contour, dimensions and proportions as to simplify and materially 40 reduce the cost of manufacture and provide for convenience and facility in assemblage.

Still further objects of the invention are 45 to provide a novel form of felly member having means for retaining a solid tread in removable association therewith; a special form of durable cushion device having advantageous resilient unifying features, and to so mount the said device as to render it readily disposable in operative position and 50 easily accessible for adjustment, repair and replacement when necessary, and to assemble the several parts in such manner that the outer side element of the wheel may be quickly detached from and reattached to the 55 remaining parts without dismantling the entire wheel.

With these and other objects which will hereinafter appear, the invention consists in the construction and arrangement of the several parts more fully described in the 60 subjoined specific disclosure of the invention and embodied in the appended claims.

The present invention also embodies a development and improvements of the structure disclosed by my pending application 65 Sr. No. 216,916, filed February 13, 1918.

In the drawing:

Figure 1 is a central transverse vertical section of a wheel embodying the features 70 of the invention.

Figure 2 is a front side elevation of a portion of the wheel shown broken away.

Figure 3 is a detail view of one of the cushion devices.

Figure 4 represents detail perspective 75 views of a part of the hub element and the central portion of the outer body plate.

The improved wheel essentially consists of a body member composed of front and rear sheet metal plates 5 and 6; a hollow annular felly member likewise comprising front and rear sheet metal plates 7 and 8; a solid tread or tire 9 held in the outer periphery of the felly member; weight stress receiving and shock and vibration absorbing resilient cushions 10, and a bearing housing 11. The bearing housing 11 with the adjacent central portions of the plates 5 and 6, provides a hub or hub element 12 to removably fit over and turn on the usual form 80 of axle end 13, the latter in the present showing in the drawing being represented as a part of a rear driving axle 14 carrying a brake drum 15. The improved wheel, 85 however, is applicable to any form of axle and may be used both as a driving wheel and as a forward wheel. The felly member 90 is mounted to bodily shift or slide within the body member, and the latter member has equal movement on the felly member. 100 The inner periphery of the felly member is normally concentric with the hub element or bearing housing, a clear space being provided and existing at all times between the inner periphery of the felly member and the hub element or bearing housing to permit the latter to have a free independent floating action or movement. The cushions 105 10 have the greater portions thereof solid and composed of rubber or other elastic material and cylindrical in form, the said cushions having a removable mounting in 110

cyindrical seats or inclosures 16, both ends of these seats being fully open and extending into apertures 17 formed in the plates 7 and 8 of the felly member. The plates 5 and 6 have coupling bolts 18 inserted therethrough and secured in such manner as to permit the outer plate 5 to be readily detached, the said bolts passing through the centers of the cushions 10, these cushions 10 and the bolts being regularly spaced in circular alinement around the wheel. The plate 5 has an outwardly struck or dished central portion 19, and the corresponding portion 20 of the plate 6 is dished outwardly, and both portions 19 and 20 being flattened as shown, to accommodate the application of the brake drum 15 to the portion 20, and between these central dished portions of the plates 5 and 6 the hub 12 as 20 a unit is confined and positively held in fixed application to resist displacement by the rotation of the axle extremity and wheel. The central dished portions 19 and 20 of the plates 5 and 6 also give ample 25 transverse distance at the center of the wheel for a practical and strong application of the hub or bearing housing of the wheel, and the preferred specific construction and arrangement of parts of the hub 30 or bearing housing will be explained more fully hereinafter. The plates 5 and 6 are also both formed with outwardly dished portions 20^a at intervals therearound in circular alinement, the said latter dished portions being directly opposite the ends of the cushion seats 16 and apertures 17 of the plates 7 and 8, the bolts 18 extending through the centers of these dished portions 20^a, to compensate for endwise bulge 35 or expansion of the cushions when under pressure stress and to avoid wear on the cushion ends, and also to give ample clearance for free movement of the felly member plates 7 and 8 between the body member plates 5 and 6. Between the dished portions 20^a the plates 5 and 6 are flat and snugly and movably embrace the plates 7 and 8 of the felly member. The bolts 18 40 positively secure the plates in separable relation for the purpose of removal, adjustment and replacement and substitution of the cushions, and moreover, said bolts hold the plates 5 and 6 in true alinement and permit them to be adjusted as may be desired and found necessary relatively to the plates 7 and 8. It will therefore be understood that the compression of the cushions 10 is effected through the bolts 18 from the axes of the cushions outwardly in radial directions toward the peripheries thereof. The cushions are not secured at their points of application except through the medium of the bolts 18, the peripheries of the said cushions removably engaging the cylindrical seats or inclosures 16 which are con-

nected to the plates 7 and 8 of the felly member. The cushions move uniformly with the felly member against the resistance of the connecting bolts 18, there being no compression, due to imposed weight or 70 otherwise, on the peripheries of the cushions. The outwardly dished portions or arches 20^a of the body plates 5 and 6, have also been provided as a strong sustaining means for the bolts 18, in view of the fact 75 that all the weight and pressure strains are imposed on said bolts and by the latter to the longitudinal centers of the cushions from the body plates and the felly plates. Another important service of the bolts 18 is 80 that they constitute bearing means for the transmission and distribution of the weight of the load from the body member to the cushions and felly member, the cushions resiliently floating the load weight or stress 85 and easing the running of the wheel. Conversely, irregularities and inequalities in the road surface will be traversed or ridden by the improved wheel with ease and shock and vibration absorbing effect through the 90 medium of the cushions arranged as specified and the relative movement of the felly and body members, the cushions taking up and counteracting as a resistance means all strain on and preventing injury to the wheel 95 organization. This self protective feature of the improved wheel is rendered more certain and reliable by the floating disposition of the hub element 12, as the range of relative movement of the felly and body 100 members will be less restricted and thereby dissipate jars or jolts, and further, the different active parts of the entire structure will be caused to wear more evenly. All 105 stresses on and applied exteriorly to the wheel will be regularly distributed, from the points of greatest intensity of application thereof, to and be taken up and absorbed by the cushions in proportion to the distances of the cushions from the said points of 110 application. In view of the spaced relation of the cushions it is obvious that the tractive pressure and shock and vibration affecting that part of the tread between the successive cushions will be taken up by the two 115 nearest cushions and proportionately by the remaining cushions around the wheel structure. In other words, the cushions coact or have a contributing function in taking care of the weight and tractive stress, and 120 shocks and vibrations, and there is never any rigid contact intermediary between the hub element 12 and the wheel tread or tire. 9. In view of this particular organization and its operation the entire load is floated 125 on resilient cushions or elements which absorb all radial torque and side thrust shocks. The cushions conjointly with the bolts 18 provide a large volume of rubber with freedom and uniformity in resilient action, and 130

these cushions being held in positive confinement in the movable felly member results in a material reduction of friction and wear. These cushions also serve as means 5 for automatically restoring the parts of the wheel to normal position when they are relieved of weight or other pressures and shocks, and thereby further induce regular or equal wear on all the wheel parts.

10 Aside from the general essential organization thus far described, there are certain advantageous specific features of construction comprised in the preferred form of the wheel structure as shown. The first of these 15 features of importance, is the cylindrical seat or mounting 16 for each cushion 10, and the cushions per se. The opposite ends of each cylindrical seat or mounting 16 are formed with circumferential grooves 21 to 20 form abutting shoulders to bear against inner opposing sides of the plates 7 and 8 around the apertures 17 to provide snug joints and bracing means between the seats or mountings and the said plates.

25 The ends of the seats or mountings 16 are flush with the outer surfaces of the plates 7 and 8 so that no obstruction may exist at these points to the free movement of the felly and body members. The coupling bolts 18 30 and seats or mountings 16 serve as very rigid bracing means between the plates 5 and 6 and 7 and 8 to resist crushing or bending stresses. Each cushion 10 has a bearing journal consisting of a central tubular member 35 22 having four radial T-arms 23 of uniform length, the member 22 extending centrally through the cushion and terminating coincidently with the opposite ends of the cushion. The arms 23 likewise extend fully 40 through the length of the cushion and terminate at the ends of the latter. The member 22 and the arms 23 are formed of suitable metal and molded in the cushion. The bolts 18 are passed through the members 22, 45 and wear directly on the rubber of the cushions is thus prevented, and furthermore, the stresses delivered to the cushions through the medium of the bolts 18 are more uniformly distributed over the interior body 50 portions of the cushions. The T-arms distribute the range of active resiliency of each cushion, for the reason that the upper vertical arm of each series thereof will pull down or drag on the part of the cushion 55 adjacent thereto, and the two horizontal arms will force down the portions of the cushion adjacent to them, thereby bringing into resilient action a greater portion of each cushion than would be the case if the 60 pull was solely from a central longitudinal point. Between the arms 23 the cushion also has openings 23^a of any preferred or suitable diameter and extending therethrough from end to end to make it more sensitively resilient and to minimize bodily lateral dis-

placement when under pressure and to compensate for relief and replacement of portions of the body of the cushion when under compression. The T-arms 23 also strengthen and increase the wearing durability of the 70 cushions.

Another advantageous means is the supporting means for the tread or tire 9. The outer or peripheral edges of the plates 7 and 8 are formed with inturned flanges 24, and at 75 the base of said flanges a sheet metal channeled inclosure 25 of circular form is interposed between the plates 7 and 8 to serve as a base support for the tread or tire 9, the flanges 26 of said inclosure being inwardly 80 disposed, and through the flanges 26 and the plates 7 and 8 bolts 27 are removably inserted at intervals and preferably with their nutted ends adjacent to the plate 7, so that after the plate 5 has been detached the plate 85 7 may be easily detached to remove and replace the tread or tire 9 or substitute one that is new for a worn one. The inner edges or peripheries 28 of the plates 7 and 8 are struck or bent inwardly to form right angular flanges and shoulders 29 to which the outwardly projecting flanges 30 of a circular sheet metal channeled inclosure 31 is secured by bolts 32 or analogous fastening means. The inclosures 25 and 31 provide 90 also for a convenient assemblage and strong construction of the felly member, and these several parts are of comparatively light weight and of ample rigidity to practically withstand the maximum stress to which 95 wheels of this type may be subjected without liability of distortion and fracture.

A further specific feature of importance is the association of the plates 5 and 6 with the bearing housing 11 and the practical 100 production of the hub element 12. The centers of the outwardly dished portions 19 and 20 of the body member plates 5 and 6 are respectively formed with openings 33 and 34 of sufficient dimensions to receive the axle 105 extremity 13 and also to provide for the mounting of the bearing housing 11. Around the openings 33 and 34 are reversely disposed inwardly bent flanges 35 and 36 which are given a square or similar angular 110 contour, as shown by Figure 4, and fitted and suitably secured in correspondingly shaped seats or grooved reductions 37 and 38 at the outer and inner ends of the housing 11 to positively hold the latter in fixed 115 position to serve as a reliable bearing in which the axle extremity 13 may be inserted. Between the axle extremity 13 and the adjacent wall of the housing 11, anti-frictional devices 39 are interposed to give the 120 wheel an easy running association with said extremity. The wheel is adapted to be applied to the axle extremity in the usual manner and held associated therewith by a specially constructed cap 125 130

nut 40 to screw to place against the flattened surface of the outwardly bent portion 19 on the screw-threaded terminal of said axle extremity; said nut having an outer 5 convex surface 41 of the same arc as the surroundings convex surface of the said portion 19 to regularly contour the contour of the said portion 19 without ridge, shoulder or broken joint. The said nut has two 10 holes or sockets 41^a in which a spanner or analogous tool may be inserted to provide a firm hold and purchase for applying or removing the same.

The outer peripheral edges and intermediate 15 portions of the body plates 5 and 6 are formed with inwardly opening corrugations 42 and 43 extending circularly over the plates to serve as pockets to receive a suitable lubricant 44 which may be of plastic 20 or cord form and exposed to and engaging the plates 7 and 8 of the felly member to ease the relative movement of the felly and body members and reduce the wear of the adjacent plates of the latter, and also to provide 25 strengthening ribs for the said plates 5 and 6.

The several main elements of the wheel consisting of the plates 5 and 6 of the body member, and the plates 7 and 8 and enclosures 30 25 and 31 of the felly member will all be shaped by suitable mechanism with economy in manufacture. The felly member, which serves as the road contact component of the wheel and receives the maximum 35 tractive-weight and other stresses thereon and therein, is prevented from buckling and distortion by insertion thereof in the body member and the bracing action of the outer and inner enclosures 25 40 and 31. In addition to the corrugations 42 and 43 serving as a strengthening means for the plates 5 and 6, the latter are also materially reinforced by the outwardly dished portions 19 and 20 and 20^a. The bolts 18 45 serve as the stress receiving and transmitting units for all parts of the wheel to the cushions 10 carried by the felly member and at the same time brace the plates 5 and 6 and have a subsidiary bracing action relatively 50 to the felly member. Wear on the cushions 10 will be minimized owing to the particular mounting and confinement and enclosure thereof as hereinbefore explained. In the event that it may be necessary to adjust 55 or replace any of the cushions, they may be readily withdrawn and reset or new ones substituted therefor in an expeditious manner. The lubricant or lubricating means may also be easily replenished when necessary.

From the foregoing it will be understood that a cushion wheel is provided complying in all respects with the prime requisites pertaining to structure and efficiency of a 60 wheel of this type; giving greater resistance

to traffic shock; providing for a minimum of soil adhesion due to the plane surfaces of the plates 5 and 6 and 7 and 8 respectively of the body and felly members; affording materially increased resiliency in 70 action, which obviously, results in better service from bearings, axles, springs, and engine, and ensures longer life in general to all parts of a vehicle equipped with the same, as well as effecting a marked reduction in the cost of upkeep by obviating the 75 commonly experienced tire troubles incident to pneumatic tubes and accessories.

In various sizes of wheels, or those respectively adapted for ordinary road and 80 touring service and for trucks, the several parts of the wheel may be varied as to dimensions and general proportions, and likewise the thickness of the sheet metal of the components of the body and felly members 85 may be increased as found necessary.

What is claimed as new is:

1. In a wheel of the class specified, a felly member having opposite flat side plates of similar form and dimensions connected by 90 outer and inner peripheral closures to provide a closed annular chamber, a solid elastic tread removably secured on the outer periphery of the felly member, the inner peripheral closure providing a wall for an enlarged opening at the center of the felly member, transversely extending cylindrical seats mounted in the felly member between the inner and outer peripheries thereof and having opposite open ends exposed through 95 the side plates of the felly member, a body member with a central hub element and spaced side plates of similar dimensions to closely and partially embrace the side plates of the felly members and always close over 100 and conceal the opposite ends of the seats, substantially solid rubber cushions loosely and removably held in the seats and terminating within the planes of the outer sides of the side plates of the felly member, the 110 felly and body members having a relative sliding and floating association and the cushions uniformly movable with the felly member, and connecting devices secured solely to the side plates of the body member and extending through the longitudinal centers of the cushions to apply all weight and stress strains at the centers of the cushions to effect a distribution of the compression outwardly toward the peripheries of the 115 cushions.

2. In a wheel of the class specified, a body member comprising side plates having outer edge and intermediate inwardly opening corrugations continuing fully therearound 120 adapted to receive lubricating material and also formed with central outwardly bent portions and intermediate outwardly bent spaced circular portions in circular alinement around the central outwardly bent portions, 125 130

- all of the corrugations and outwardly bent portions serving as reinforcing and stiffening means for the said plates and the central outwardly bent portions also acting as inclosing spaced means, a felly member having a plurality of cushions therein terminally disposed opposite the said outwardly bent circular portions of the side plates of the body member, and connecting bolts extending through the centers of and sustained by the said outwardly bent circular portions and through the longitudinal centers of the cushions and applying all of the weight and strain stresses to the said centers of the cushions to effect an outward distribution thereof toward the cushion peripheries. 30
3. In a wheel of the class specified, a felly member, a body member having a hub element, the felly member being movably mounted in the body member, a plurality of compressible cushions having the greater portions thereof solid and mounted in the felly member and each having a central tubular bearing with a plurality of radial T-arms 35 extending therefrom and imbedded in the cushions, and connecting devices between the opposite sides of the body member and extending through the tubular bearings of the cushions, the connecting devices through the
- tubular bearings and radial T-arms uniformly distributing the compressing stresses, established by the weight affecting and moving the body and felly members, throughout the cushions. 30
4. In a wheel of the class specified, a felly member, a body member having a hub element, the felly member being mounted in the body member and the two members having relative sliding association, a plurality of compressible cushions mounted in the felly member and each having a central bearing opening and a plurality of compression compensating openings around the central opening, all of the openings extending longitudinally through the cushions from end to end thereof, each cushion also having a central bearing with a plurality of radial T-arms extending therefrom and embedded in the cushion between the compression compensating openings and connecting devices 45 between the opposite sides of the body member and extending through the central bearing openings of the cushions. 45
- In testimony whereof I have hereunto set my hand in presence of a subscribing witness. 50
- GEORGE E. HOARD.

Witness:

JOHN L. FLETCHER.
